(57) CLAIM

The ornamental design for a shoe sole, as shown and described.

DESCRIPTION

FIG. 1 is a front right-side perspective view of a shoe sole showing our new design;

FIG. 2 is a front perspective view thereof;

FIG. 3 is a rear perspective view thereof;

FIG. 4 is a right-side perspective view thereof;

FIG. 5 is a left-side perspective view thereof;

FIG. 6 is a top perspective view thereof; and,

FIG. 7 is a bottom perspective view thereof.

FIGS. 1-7 depict a first embodiment of a design for a right shoe sole; a second embodiment is a left shoe sole, which is a mirror image thereof.

The broken lines appearing in FIGS. 1-6 form no part of the claimed design. The broken lines that show the remainder of a shoe show environment and form no part of the claimed design. The broken lines crossing claimed surfaces show environment and form no part of the claimed design.

1 Claim, 7 Drawing Sheets
